UNITED STATES PATENT OFFICE.

WILLIAM A. HAZLEWOOD, OF FORT WORTH, TEXAS, ASSIGNOR OF ONE-HALF TO J. ADO WHITESIDE, OF FORT WORTH, TEXAS.

LOCOMOTIVE DRIVING-BOX.

1,227,907.

Specification of Letters Patent. Patented May 29, 1917.

Application filed August 4, 1916. Serial No. 113,113.

To all whom it may concern:

Be it known that I, WILLIAM A. HAZLEWOOD, a citizen of the United States, residing at Fort Worth, in the county of Tarrant and State of Texas, have invented a new and useful Improvement in Locomotive Driving-Boxes, of which the following is a specification.

My invention relates to a detachable flange 10 for locomotive driving boxes, and the object is to provide a simple detachable flange for locomotive driving boxes which can be quickly and easily removed for renewal of bearings, shoes, wedges, and associated elements. The principal advantage of such a detachable flange is the time saved in removing the same for its own repair or renewal, or any of the coöperating parts and the saving in time and avoidance of expense 15 in taking down various other parts which coöperate therewith and restoring such parts. Other objects and advantages will be fully explained in the following description and the invention will be more particularly pointed out in the claims.

Reference is had to the accompanying drawings which form a part of this application.

Figure 1 is a side elevation, showing the 20 flange in place. Fig. 2 is a similar view, showing in dotted outline, one of the members of the flange raised or swung upwardly and outwardly on its pivot bolt. Fig. 3 is a vertical cross-section, taken on the line *c-c* 25 of Fig. 1. Fig. 4 is a horizontal section, taken on the line *A-A* of Fig. 1, showing the upper part of the box and the flange. Fig. 5 is a plan view of the box with the flange applied. Fig. 6 is a side elevation of 30 the box and the flange, being a view at right angles to Fig. 1.

Similar characters of reference are used to indicate the same parts throughout the several views.

45 A box *E* of ordinary type is shown in the drawings, having integral flanges *C* and detachable flanges *A* and *B*. Grooves *F* are formed in the vertical sides of the box *E* and the detachable flange, composed of mem-

bers *A* and *B* have vertical ribs or flanges *G* 50 which occupy the grooves *F*. The members *A* and *B* are pivotally connected together on top of the box, preferably at the middle point of the top part of the box *E* by a pivot bolt *H*. At the lower side of the box member, the members *A* and *B* are secured rigidly to the box by a rod *D* with nut *K*. The flange members *A* and *B* are easily and quickly removed by removing the nut *K* and the rod *D*. 55

Various changes in the sizes, proportions and construction of the different parts may be made without departing from my invention.

What I claim, is,—

1. A driving box for locomotives having a detachable flange on the hub side thereof and vertical grooves in the sides thereof, made in two parts and joined together at the top and middle of said box by a rivet 70 or bolt, the said flange having a rib on each part fitting into said grooves, and joined at the bottom with a bolt passing through the flanges with a nut on the end thereof.

2. A driving box for locomotives having 75 a detachable flange composed of two members pivotally connected together on top of the box, said box having vertical grooves in the sides thereof, each member having a rib thereon and said ribs fitting in said grooves, 80 and a rod securing said flange members on said box at the lower side thereof.

3. A driving box for locomotives having 85 a detachable flange composed of two members pivotally connected together and engaging the upper side of the box, said box having vertical grooves in the side thereof and said members having portions thereof fitting in said grooves, and means for binding said members on said box. 90

In testimony whereof, I set my hand in the presence of two witnesses, this the 12th day of June, A. D. 1916.

WILLIAM A. HAZLEWOOD.

Witnesses:

J. ADO WHITESIDE,
S. J. LITTLE.
